UNITED STATES PATENT OFFICE.

PHILIP SUKERT, OF CHICAGO, ILLINOIS.

CIGAR-BOX GLASS-COVER-LOCKING DEVICE AND WOODEN-CIGAR-BOX COVER PROTECTOR.

Application filed December 2, 1925. Serial No. 72,829.

This invention relates to attachments for cigar boxes, and more particularly to what I term a cigar box glass cover locking device and wooden cigar box cover protector.

One of the main objects of the invention is to provide a device of simple and inexpensive construction which can be readily applied to the wooden covers or lids of cigar boxes in such manner as to effectually brace the cover during handling of the box, this means also serving to normally hold the cover in open position. A further object is to provide a device of the character stated including simple and efficient means for locking the wooden cover or lid against rearward movement, such locking means being positioned in the rear of the box so as not to be readily accessible from the front thereof. Further objects will appear from the detailed description.

In the drawings:

Fig. 1 is an elevation of the device as applied taken from the rear of the box.

Fig. 2 is a section taken substantially on line 2—2 of Fig. 1.

Fig. 3 is a section taken substantially on line 3—3 of Fig. 1.

Fig. 4 is an end view of the box showing the device as applied.

The device is intended to be applied to a cigar box 1 of standard construction, this box including a wooden cover or lid 1^a hingedly secured to the box in a known manner. The device includes two telescoping members 2 and 3 of channel cross section provided at their outer ends with hook shaped elements 2^a and 3^a, respectively, these elements being adapted for engagement about the end portions of the box lid 1^a. A brace plate 4 is hingedly secured at its lower end to a locking block 5 of shallow box-like construction by means of a pintle 6. A locking bar 7 of angle cross section is associated with a key 8 which is threaded upon a screw 9 passing through aligned slots 9^a in the sections 2 and 3 of the telescoping members, these slots extending longitudinally of the members. The key 8 conforms in cross section to the cross section of locking bar 7 and fits snugly therein. The device is applied by turning bar 7 in a counter-clockwise direction as considered in Fig. 1 so as to thread this bar and the key 8 off of screw 9 sufficiently to permit relative movement 55 of the sections 2 and 3. After this has been

done the sections are extended so as to fit about lid 1^a, after which the two sections are moved toward each other so as to cause the hook elements 2^a and 3^a to engage about the lower end portions of the lid. The locking bar 7 is then threaded onto the screw 9 so as to cause binding between sections 2 and 3. When this bar is turned into vertical position as illustrated it extends across the hinge connection between brace plate 4 and locking block 5 so as to effectually hold these members against relative movement about pintle 6. This holds lid 1^a of the box in vertical or open position and effectually locks the lid against downward and rearward movement. When it is desired to move the lid 1^a downwardly and rearwardly bar 7 is turned in a counter-clockwise direction as considered in Fig. 1 into horizontal position, thus permitting relative movement between plate 4 and block 5 about pintle 6, which permits the lid to be moved downwardly and rearwardly of the box into substantially the dotted line position illustrated in Fig. 4, during which movement the block 5 is moved upwardly into substantially the position indicated. It is also to be noted that the plate 4 extends to within a short distance of the upper edge of lid 1^a. In handling the box the plate 4 and lid 1^a are grasped so that this plate acts to very materially reinforce the lid and eliminates danger of breakage thereof.

This device is intended more particularly to be used in connection with a closure member or cover of glass or other suitable transparent material which is secured to lid 1^a in any suitable or preferred way and in such manner that when the lid 1^a is tilted rearwardly beyond vertical position the cover or closure member will be raised so as to permit access to the box. Preferably the closure member or cover is secured to the lid in the manner disclosed in my application for cigar box moistener and cover, executed May 5, 1926, though this cover may be secured to the lid for movement therewith in any other suitable manner. In Fig. 4 I have indicated the cover 10 in the position which it occupies when the lid 1^a is moved downwardly and rearwardly into the position indicated by dotted lines. When the lid 1^a is raised into vertical position the cover 10 fits over the box so as to close the same. By turning locking bar 7 into vertical po-

sition the lid 1^a is locked against downward and rearward movement thus locking the cover 10 in closed position. This effectually prevents the box from being surreptitiously opened and cigars abstracted therefrom by unauthorized persons.

To release cover 1^a for opening the box, locking bar 7 is turned into horizontal position in the manner previously stated, the 10 key 8 facilitating turning of the bar. Preferably, though not necessarily, the bar 7 and key 8 are sufficiently loose on screw 9 to permit the bar to turn downwardly by gravity into locking or vertical position 15 when it is released. This insures that the bar is normally in locking position so as to lock the lid 1^a against downward and rearward movement. It is also preferred to provide the locking bar 7 with a plurality 20 of spaced openings, as illustrated in Fig. 1, for reception of screw 9. The bar can thus be adjusted to suit boxes of different heights and, as the members 2 and 3 can be adjusted toward and away from each other, this 25 adapts the device for attachment to boxes of various sizes.

What I claim is:

1. In a device of the character stated, two hingedly connected members, means for attaching one of said members to a cigar box lid, and means for locking said members against relative movement about their hinged connection.
2. In a device of the character stated, 35 a brace plate, a locking block hinged at its upper end to the lower end of the brace plate, means for attaching the plate to the lid of the cigar box, and a locking bar pivoted to the plate and movable into and 40 out of position to extend across the hinged connection between the plate and the block.
3. In a device of the character described, a member adapted for attachment to a cigar box lid, a brace plate carried by said mem-

ber, a locking block hingedly secured at its 45 upper end to the lower end of the plate, and a locking bar pivotally connected to the plate and movable into and out of position to extend across the hinged connection between the plate and the block. 50

4. In a device of the character stated, two telescoping members having elements adapted for engagement about the end portions of a cigar box lid, said members being aligned slots, a brace plate disposed transversely of the telescoping members, a locking block hingedly secured to the plate, a pivot member extending through the brace plate and the slots of the telescoping members, and a locking bar mounted on the pivot member and movable into and out of position to extend across the hinge connection of the plate and the block. 55

5. In a device of the character stated, a brace plate, a locking block hingedly secured to the lower end of the plate for movement about an axis disposed transversely thereof, means for attaching the brace plate to a cigar box lid, and a locking bar carried by the plate and movable into 60 and out of position to extend across the hinge connection between said plate and the block. 65

6. In a device of the character stated, two telescoping members having at their outer 75 ends elements adapted for engagement about the end portions of a cigar box lid, said members being provided with aligned slots, a brace plate disposed transversely of the telescoping members, a screw passing 80 through the brace plate and through the slots of the telescoping members, a locking block hingedly secured to the lower end of the brace plate, and a locking bar threaded on the screw and movable into and out of position to extend across the hinge connection between the plate and said block. 85

PHILIP SUKERT.
